VARIABLE LENGTH TORPEDO HEAD

Thomas C. Boyle, Altadena, Calif.

Application October 13, 1949, Serial No. 121,082

2 Claims. (Cl. 114—20)

(Granted under the act of March 3, 1883, as
amended April 30, 1928; 370 O. G. 757)

1

This invention relates to torpedo construction and more particularly to a new and improved exercise head therefor.

It is customary practice to test the power plant and steering mechanisms of torpedoes by substituting an exercise head for the usual war head and giving the torpedo a trial run or series of such runs. In carrying out such tests it is essential that the exercise head have substantially the same weight and buoyancy characteristics as the war head so that the test run will duplicate, as closely as possible, the operating conditions of the torpedo when used for destructive action. These exercise heads are usually hollow shell-like members which are filled with liquid ballast to provide proper weight. At the end of the test run the liquid in the exercise head is automatically expelled through an outlet valve by air pressure entering the head from an air flask. As the liquid is replaced by air, the weight, of course, is reduced and the torpedo becomes buoyant and rises to the surface. This permits the torpedo to be easily located and recovered.

Exercise heads of this character may be reused for test or practice purposes so long as they are not damaged and provided they are used to replace war heads having substantially the same dimensions and buoyancy characteristics. In the past any substantial changes in the war head, such as modifications in design, loading, etc., required corresponding changes in the exercise head which was to serve as a substitute in the exercise runs. This entailed the fabrication and stocking of a large number of such exercise heads with the attendant cost in time, materials and storage space.

An object of the present invention is to provide a torpedo exercise head that is adjustable so that it may be used as a replacement for a variety of war heads. Another object is to provide a head of this character whose overall length may be changed as required.

A further object is the provision of a torpedo exercise head made up of a plurality of sections which may be individually replaced.

Other objects and attendant advantages of the invention will become more apparent from the following description read in conjunction with the accompanying drawing, in which:

The single figure is a longitudinal view partly in section showing the structural details of the invention.

In the embodiment illustrated in the drawing the torpedo exercise head of the present invention comprises a closed hollow shell-like struc-

2

ture made up of a plurality of sections. These sections are rigidly retained in assembled relation by means hereinafter described. The head includes a nosepiece 10 which may be molded or cast of any suitable material and is formed with the usual ogive contour on its forward exterior surface. Projecting rearwardly from the ogive portion of the nose and integral therewith is a cylindrically shaped extension 11 the outer diameter of which is somewhat smaller than the major diameter of the nose so that a shoulder 12 is provided at the juncture of the nose and extension. Suitable interior reinforcing ribs may be cast integral with the nose and extension as shown. A body member 13 cylindrical in shape and closed at its rear end in the conventional manner such as by a plate 14 has a bore 15 at its front end corresponding to the outer diameter of the extension and is adapted for telescopic engagement therewith.

A spaced ring 16 which in actual practice will be of any suitable width to provide an exercise head of the desired overall length closely fits about the outer diameter of the extension and is interposed between shoulder 12 and the front end of body 13. Suitable seals 17 such as those of the "O" ring type made of rubber or similar material may be provided as illustrated in order to make a fluid tight construction.

The nose 10, body 13 and spacer ring 16 may be held in assembled relation by a shaft 18 extending axially of the chamber 19 formed by the assembled members and connected at one end to the nosepiece and at the other end to the body. As shown in the drawing the left end of shaft 18 extends through an opening in the hub of a spider 20 the legs of which are rigidly secured at their extremities to an internal flange 21 in the nose by bolts 22. A plate 23 having a central opening through which the end of the shaft projects slightly may be attached to the central portion of the spider by bolts 24. The projecting end of the shaft may be rigidly attached to plate 23 by welding or other well known means.

The opposite end of shaft 18 may be supported in a bearing 25 having an axial opening therethrough. As illustrated, bearing 25 may be cast integral with body 13 and is rigidly supported in its central position by a pair of oppositely disposed arms 26 extending inwardly at an angle from the inner wall of the body to the bearing. Relative rotation of the nose and body members may be prevented by providing the shaft 18 with splines as shown in the drawing

with an appropriately slotted opening in bearing 25 to match the splines on the shaft.

The right end of shaft 18 is internally threaded to receive a cap screw 27 which abuts against a spacing washer 28 interposed between the end of bearing 25 and the head of the screw to prevent longitudinal movement of the shaft. Since shaft 18 is rigidly attached to nose 10 in the manner described above, it will be seen that spacer ring 16 will be locked between the shoulder 12 and the left end of body 13, thus relative movement of these members will be prevented.

It will be apparent that the overall length of the head may be readily increased or decreased to provide a ballast chamber 19 of the desired capacity by using a spacer ring 16 of the required width with suitable washers 28. Obviously, if relatively large variations in length are to be obtained shaft 18 may be modified accordingly or different length cap screws used.

It will be noted that the outside of the forward end of body 13 is tapered slightly to a diameter substantially the same as the major diameter of the nosepiece 10. Thus, when ring 16 is omitted from the assembly in order to provide a head of minimum length, the end of body member 13 will abut against shoulder 12 and there will be a continuous surface with the proper streamline effect.

With a spacer ring 16 interposed between shoulder 12 and the end of body 13 as shown in the drawing the gap resulting from the difference in size of the ring and the end of the body may be covered by a tubular skirt 29 affixed to the spacer ring by screws 30 and extending rearwardly about the body to maintain the proper streamline effect.

From the foregoing description it will be understood that the present invention contemplates an exercise head which may be readily extended in length as required and, further that such adjustment may be made without destroying or changing the streamline effect which is necessary with this type of device.

With the exercise head attached to the air flask section of the torpedo in the manner well known in the art, the chamber 19 which extends the length of the head may be filled with a suitable liquid ballast in order to provide the proper weight and buoyancy characteristics to the torpedo to which it is attached. In making the practice or trial run the exercise head operates in the well known manner. As the torpedo reaches the end of the run, a valve 31 connected by suitable piping to the air flask (not shown) is adapted to release air into chamber 19. The pressure of the incoming air causes an outlet valve 32 to open and the liquid ballast is thus discharged. When a substantial amount of ballast has been released and the exercise head is filled with air the torpedo to which it is attached becomes more buoyant and rises to the surface.

It should be understood, of course, that the foregoing disclosure relates to only a preferred

embodiment of the invention and that numerous modifications or alterations may be made therein without departing from the spirit and scope of the invention as set forth in the appended claims.

The invention described herein may be manufactured and used by or for the Government of the United States of America for governmental purposes without the payment of any royalties thereon or therefor.

What is claimed is:

1. In an exercise head for torpedoes, a nosepiece, an extension affixed to said nosepiece, a body member in telescopic engagement with said extension, a spacer ring between said nosepiece and said body, a bearing supported in said body, a shaft affixed at one end to the nosepiece and supported at its other end in the bearing, and a threaded member in the end of said shaft engaging the end of the bearing for locking the shaft against longitudinal movement.

2. In an exercise head for any given one of a plurality of torpedoes of uniform diameter but differing in length; a nosepiece comprising a forwardly pointed ogival hydrofoil portion and a rearwardly extending cylindrical telescopic portion of uniform diameter less than that of the ogival hydrofoil portion, said nosepiece being formed with a rearwardly facing annular shoulder at the juncture of said forward and rearward nosepiece portions; a cylindrical body member having an outer hydrofoil surface terminating at one end in a forwardly facing annular shoulder defining an opening telescopically receiving the cylindrical portion of said nosepiece; a spacer ring encircling said cylindrical portion between said annular shoulders, said ring being of a width chosen to fix the overall length of said exercise head commensurate with the length and buoyance characteristics of said given torpedo and being provided with an exterior hydrofoil surface forming a continuous streamline contour with said nosepiece hydrofoil portion and the outer hydrofoil surface of said body member upon interposition therebetween; and releasable fastening means drawing said nosepiece and body member into a telescoped positional relationship such that said spacer ring is tightly clamped between said annular shoulders.
